UNITED STATES PATENT OFFICE.

THOMAS W. HOLT, OF ELKHART, INDIANA, ASSIGNOR TO CURTAIN SUPPLY COMPANY, OF ELKHART, INDIANA, A CORPORATION OF ILLINOIS.

SASH GUIDE.

Application filed May 25, 1925. Serial No. 32,536.

The present invention has to do with sash guides, and is particularly concerned with an improved guide which is adapted to be embraced between the side walls of a groove 5 in the stile of a sash.

The principal object of the invention is to provide a guide of the character described which is of extremely simple construction, which may be manufactured at a very low 10 cost, and which will afford a weather-proof closure for a sash.

Another object of the invention is to provide such a guide which is expandable both laterally of the sash and in the plane of 15 the same.

Still another object is to provide such a guide which will allow additional clearance at the bottom between the sash and the sill.

Other objects and advantages of the 20 invention will undoubtedly occur to those skilled in the art upon a comprehension of the novel features of the guide.

In order that the invention may be readily understood, four slightly different embodiments of the same are presented as exemplifications in the accompanying drawings and in the following detailed description based 25 thereon.

In the drawings:

Fig. 1 is a view of a corner of a window sash associated with a guide constructed in accordance with the invention;

Fig. 2 is an interior view of one form of the guide;

Fig. 3 is a side view of the same;

Fig. 4 is a transverse section taken through the sash and guide at one point;

Fig. 5 is an interior view of another form of the guide;

Fig. 6 is a side view of the same;

Fig. 7 is a transverse section taken through the sash and guide, in that form of the latter shown in Figs. 5 and 6;

Fig. 8 is an interior view of another form of the guide;

Fig. 9 is a side view of the same;

Fig. 10 is a transverse section taken through the sash and guide, in that form of the latter shown in Figs. 8 and 9;

Fig. 11 is a front view of another form of the guide;

Fig. 12 is a side view of the same;

Fig. 13 is a transverse section taken through the sash and guide at one point, in

that form of the latter shown in Figs. 11 55 and 12; and

Fig. 14 is a similar section taken at another point.

The form of the invention illustrated in Figs. 1 to 4 inclusive will first be described. 60 It will be observed that the guide of the invention is attached to the jamb 10 of a window frame, and is embraced between the side walls 11 of a groove in the stile 12 of a window sash.

The guide consists of a rigid channel strip 13 which is secured to the jamb 10 by means of a number of machine screws 14. The strip 13 is preferably arranged with the base 15 of the strip spaced from the jamb 10, and 70 with the side walls 16 and 17 of the strip in abutment with the jamb, whereby to present a guide rib of box-like form. The strip may also be arranged, however, with the base 15 against the jamb. 75

A number of bowed leaf springs 18 are secured by rivets 19 or other suitable means to the side wall 17 of the strip, and bow laterally through apertures in the side wall 16. The portions of the springs 18 exposed 80 through the apertures in the strip 13 constitute sash-engaging elements which are adapted to bear at intervals under spring pressure against one of the side walls 11 of the groove in the stile of the sash, and the 85 outside face of the side wall 17 of the strip is adapted to bear contiguously against the other side wall 11 of the groove in opposition to the action of the springs 18.

It will be understood from the foregoing 90 description that the guide provides a rigid stop for the sash in one lateral direction and a yielding support for the same in the opposite lateral direction, and affords a spring-pressed weather-proof closure between the 95 guide and the sash throughout the vertical extent of the latter.

In Figs. 5 to 7 inclusive is shown a slightly modified form of the guide wherein the springs 18 of the previously described form 100 are eliminated, and a number of sash-engaging shoes 20 are instead used. The shoes 20 are pressed laterally through apertures in one side wall of the strip 13 by means of small coil springs 21, and are guided in such 105 movement by laterally extending portions 22 which slidably engage with the ends of the apertures in the side wall. The ends 23

of the shoes 20 are bent in opposite directions beyond the ends of the apertures in the side wall to limit the lateral movement of the shoes 20 under the action of the springs 21.

5 In Figs. 8 to 10 inclusive is shown another form of the guide which differs from the first described form only in that a channel strip 24 of tapered shape is used in place of the strip 13. The strip 24 tapers toward the bottom of the same in order to allow more clearance between the sash and the sill.

In Figs. 11 to 14 inclusive is shown still another form of the guide. A channel strip 25 is secured to the jamb 10 with the base 15 26 of the strip seated against a strip 27 of compressive weather-proofing material interposed between the guide and the jamb. A number of leaf springs 28 are secured to one side of the wall 29 of the strip and bow 20 laterally through apertures in the other side wall 30 of the strip into spring-pressed engagement with one of the side walls 11 of the groove in the stile of the sash. Other leaf springs 31 are secured between the 25 springs 28 to the base 26 of the strip and bow outwardly from the channel in the strip into spring-pressed engagement with the base 32 of the groove in the stile of the sash. A folded strip 33 of a resiliently yieldable 30 fabric or other suitable material is secured within the channel of the strip against the side wall 30 of the strip, and projects outwardly from the channel into continuous engagement with the base 32 of the groove.

35 In this form of the guide, the springs 28 engage with one of the side walls 11 of the groove in the stile of the sash, the side wall 29 of the strip bears continuously in a weather-proof joint against the other side 40 wall 11 of the groove, the springs 31 engage with the base 32 of the groove to center the sash between the two sash guides on the spaced jambs of the window frame, and the strip 33 bears continuously in a weather- 45 proof joint against the base 32 of the groove, thereby affording a thoroughly sealed but resiliently yieldable association between the sash and the guide.

I claim:

50 1. A sash guide, comprising a rigid channel strip of tapered formation adapted to be attached to a window jamb with the smaller end of the strip at the bottom of the jamb and a plurality of spring-pressed sash- 55 engaging elements secured within the strip and projecting from the contour of the same.

2. A sash guide, comprising a rigid U-shaped channel strip in which the sides of the channel converge toward one end of the

strip whereby to produce a guide of tapered 65 formation.

3. The combination with a sash having a groove in one edge thereof, of a guide, comprising a rigid channel strip adapted to be attached to a window jamb and contained 65 within the groove, and a plurality of spring-pressed sash-engaging elements secured within the strip and projecting from the same, said elements being so arranged as to press the sash laterally against one side of 70 the strip.

4. The combination with a sash having a groove in one edge thereof, of a guide, comprising a rigid channel strip adapted to be attached to a window jamb and contained 75 within the groove, and a plurality of spring-pressed sash-engaging elements projecting laterally through apertures in one side of the strip to press the sash laterally against the other side of the strip. 80

5. The combination with a sash having a groove in one edge thereof, of a guide, comprising a rigid channel strip adapted to be attached to a window jamb and contained within the groove and a plurality of leaf 85 springs secured within the channel against one side of the strip and projecting laterally through apertures in the other side of the strip to press the sash against that side of the strip to which the springs are secured. 90

6. The combination with a sash having a groove in the stile thereof, of a guide comprising a rigid channel strip adapted to be attached to a window jamb and contained within the groove, and a plurality of leaf 95 springs secured within the channel against one side of the strip with intermediate portions of the springs bowed laterally through apertures in the other side of the strip, said intermediate portions being so arranged as to press the sash laterally against that side of the strip to which the springs are secured. 100

7. The combination with a sash having a groove in the stile thereof, of a guide, comprising a rigid channel strip adapted to be attached to a window jamb with the base of the strip in spaced parallel relation to the jamb to present a box-like guide rib for reception within the groove, and a plurality of spring-pressed sash-engaging elements projecting laterally through apertures in one side of the strip into engagement with one side of the groove in the sash to press the other side of the groove against the other side of the strip. 110 115

In testimony whereof I have hereunto subscribed my name.

THOMAS W. HOLT.
